UNITED STATES PATENT OFFICE

JOSEPH H. GRANDE, OF SALINAS, CALIFORNIA

REFRIGERATOR SHIPPING CRATE

Application filed August 11, 1930. Serial No. 474,462.

The object of my invention is to enable the shipment of fresh vegetables over long routes without injury or deterioration from their presence in temperatures that otherwise would be hurtful and to accomplish this important object by packing means of simplicity and low cost. My invention is embodied in a refrigerator crate in which the fresh vegetables are placed in superimposed horizontal layers or tiers and layers of ice, the layers being separated by horizontal partition sheets and an important feature of my invention is these separating or partition sheets.

15 My invention consists in whatever is described by or is included within the terms or scope of the appended claims.

In the drawing—

Fig. 1 is a vertical section through a packed refrigerator crate embodying my invention;

Fig. 2 is a section on the line 2—2 of Fig. 1;

Fig. 3 is a top plan view showing the procedure in applying the packing sheets that, in effect, line the walls of the crate or container;

Fig. 4 is a plan view of one of the partition or separator sheets.

30 The shipping box or crate, 10, shown is of cubical form with end, side and bottom walls and being of ordinary construction.

The vertical walls and bottom are lined or covered with liquid-proof sheets of card-35 board. These sheets, 11, are of such form and number that by folding they cover the entire inner sides of the crate and the bottom. Necessarily certain of the sheets extend at right angles to others. The top por-40 tions of the sheets are carried over the top edges of the crate walls and lap down over the outer sides thereof. Afterwards, when the crate is packed, some of the top flaps are folded back over the top, as indicated 45 in Fig. 3, one flap lying upon another when all are folded over.

Within the lined walls of the crate vegetables, such as heads of lettuce, L, for example, are packed in horizontal layers one 50 above the other with layers of ice. Thus a

horizontal thin layer of cracked ice, 12, is first placed in the lined bottom; then a layer of vegetables, lettuce for example, is placed upon the layer of ice, then upon the layer of vegetables is placed another thin layer of cracked ice, and upon the latter is placed a division or partition sheet, 13, of cardboard or paper that extends entirely across between the side walls and is perforated by numerous V-shape slits, 14. Upon the lowest partition sheet is placed another layer formed of cracked ice, 12, at the bottom and top and vegetables and this arrangement is repeated until the crate is filled to the top.

Preferably the partition sheets are of or contain a material which makes such sheets heat insulators, thus preventing the rapid melting of the ice, and enables them to retain their stiff, flat form against what would otherwise be the disintegrating effect of the absorption of moisture by the cardboard. The moisture taken up or absorbed by them aids in keeping the vegetables fresh and crisp. The partitions being interposed between adjacent layers of ice, injurious effect of too much ice in contact with the vegetables is avoided. The openings in the form of slits effect a certain control of the quantity of water passing through the perforations because with an excess quantity of water, the material adjacent the slits will swell and tend to close up the slits so that the water will drip slowly through the slits and thus be most advantageously utilized on the vegetables. The cutting of the fibers by the slits facilitates absorption of water through the edges of the slits and thus in a way effects the storage of water in the partitions in contact with the vegetables.

What I claim is:—

1. A refrigerator shipping crate having horizontal partitions interposed between horizontal layers of vegetables and cracked ice, such partitions having slit-form perforations.

2. A refrigerator shipping crate having horizontal partitions interposed between horizontal layers of vegetables and cracked ice.

ice, such partitions having slit-form perforations of V-shape.

3. A refrigerator shipping crate having bottom and side walls with moisture-proof linings and partitions of paper separating horizontal layers of vegetables and cracked ice and extending between the crate walls, there being between two partitions two layers of ice between which is a layer of vegetables and such partitions having slit form perforations.

4. A refrigerator shipping crate comprising an external container with moisture-proof internal wall surfaces, horizontal layers of vegetables, horizontal layers of cracked ice lying in contact with the layers of vegetables and partitions interposed between adjacent layers of cracked ice, said partitions having perforations of restricted capacity to allow down flow of water from melting ice in contact with vegetables.

In testimony whereof I hereunto affix my signature.

JOSEPH H. GRANDE.
